STEAM SEPARATOR

Palmer B. Place, Tenafly, N. J., assignor to Combustion Engineering Company, Inc., New York, N. Y., a corporation of Delaware

Application August 19, 1941, Serial No. 407,387

6 Claims. (Cl. 122—491)

This invention relates to the art of steam separation in steam boilers.

In the operation of steam boilers the concentration in the boiler water, of dissolved salts, suspended matter, and the like, steadily increases, and as the concentration thereof increases so does the tendency toward foaming in the steam and water drum or drums in which the steam is separated, and in which the concentration is higher than in other portions of the boiler. In consequence, the "carry-over" in the separated steam of water with dissolved solid matter and impurities, increases with detrimental results. Thus it becomes necessary to "blow down" the boiler which involves losses due to the discarding of the boiler water and the chemicals added thereto for treatment.

I am aware that it has heretofore been proposed to provide separators for the steam and water drums of boilers, to separate out the water entrained with the steam, and such devices are effective to a certain degree. These operate by change in direction of steam flow (see, for example, the United States patent to Kerr, No. 1,901,912, of March 21, 1933).

It is the primary object of the present invention to make it possible to allow the concentration to increase to a point far above that at present permissible, as will further appear.

How the foregoing, together with such other objects and advantages as may hereinafter appear or are incident to my invention, are realized, is illustrated in the accompanying drawings, wherein—

Figure 1 is a cross-section through a steam and water drum more or less diagrammatically illustrating the invention, and

Figure 2 is a fragmentary section taken on the line 2—2 of Figure 1.

Figure 3 is a cross section similar to Figure 1 but illustrating a modification of the invention, and

Figure 4 is a cross section through a drum illustrating still another modification, in this instance in somewhat greater detail.

In the arrangement of Figure 1 a plurality of rows of tubes 7 deliver a mixture of steam and water into the steam drum A. In this instance, there are four rows of such tubes, which is a customary arrangement. These tubes deliver a relatively high velocity mixture, such as the mixture from an upright water wall section or sections of a boiler furnace or other tubes of the boiler subject to radiant heat. In this instance, the three uppermost rows of tubes 7

deliver steam and water mixture into the space above the normal water level 8 of the drum, the lowermost row delivering below the normal water level.

5 Downcomer tubes 9 return water from the steam drum to other portions of the boiler. For purposes of illustration but one row of such downcomer tubes is shown. It is to be understood that the number of rows of such tubes will vary with the particular installation, as is well understood in the art.

In addition to the inlet tubes 7, it is also to be understood that the boiler may have other inlet tubes (not shown), connected into the drum for 15 delivering relatively low velocity steam and water mixture from portions of the boiler subject to convection heat. These likewise deliver into the drum below the normal water level. The number of such tubes will also vary with the particular installation.

In an upper part of the drum there is provided 20 steam outlet means, in this instance a single row of tubes 10. Here, again, it is to be understood that the number of rows of such tubes 25 will vary with the particular installation.

Located within the drum and above the normal water level thereof is a main partition member or baffle 1 which extends longitudinally of the drums. The rear portion 1b of this baffle inclines upwardly to the wall of the drum. The front or free end portion 1a of the baffle 1 inclines upwardly but terminates short of the drum wall so as to provide an opening or passage 11 to be hereinafter more particularly referred to.

Above the baffle 1 is a second partition member or baffle 2 which extends downwardly from the drum wall from a point adjacent the row of tubes 10 and on that side of such row which is toward the rows of tubes 7. This baffle 2 likewise extends longitudinally of the drum and inclines rearwardly and downwardly. It is spaced from the portion 1a of the baffle 1 and terminates well above the horizontal portion of the baffle 1. Substantially semi-circular upright end plates 12 extend downwardly from the top portion of the drum wall to a point below the normal water level of the drum, as shown in Figure 2.

The main baffle 1 cooperates with the end plates so as to partition the space above the water into two general spaces, i. e., a space B below the baffle which constitutes a separation space of substantial size, and a space C above the baffle. Communication between the space B and the space C above the baffle 1 is afforded by the

opening or passage 11 hereinbefore referred to. That portion of the separation space B defined by the upwardly inclined portion 1a of the baffle, the end plates, and the water, may be termed a throat B', which constricts in a direction away from the tubes.

It will be seen that the three uppermost rows of tubes 7 discharge directly into this throat. These tubes have the usual spacing for ligament strength. It will be seen that the individual jets or streams of steam and water mixture delivered by such tubes, spread, fan out or bush so that they merge into one another at a point somewhat in advance of the dot and dash line 13, and also that the jets or streams delivered by the uppermost row of such tubes 7 impinge on the portion 1a of the baffle at a point in advance of the line 13. Such portion 1a is of such length and is so located with reference to the drum wall and the tubes 7 as to cause such impingement to occur at a point intermediate the ends of the portion 1a and well removed from each end. The inclination of the portion 1a is such that the impingement occurs at a small angle.

In consequence, at approximately the plane of line 13, the individual jets or streams merge to form and to maintain a moving but continuous sheet or screen or barrage of steam and water, i. e., a barrage which is continuous across the throat—from portion 1a to the water level and from one end plate or baffle 12 to the other end plate or baffle. The screen or barrage is also of considerable depth as it only dissipates after entrance into space B, proper.

In the region of the line or plane 13 and from thence on, the steam, being lighter, tends to slow up somewhat, but the water in the mixture, being heavier, tends to proceed in its initial downward direction at substantially its initial velocity, until it joins the water in the drum.

Due to the foregoing, a number of things occur. In the first place, there is a separation of water from the steam and water mixture delivered into the throat, because, as just above described, water in such mixture continues on to join with the water in the drum, and the steam in such mixture enters the space B proper. In the next place, it will be seen that the screen or barrage moves in a direction directly counter to the flow of steam leaving the space B on its way to the opening 11. Thus any water in the steam so leaving the space B proper receives the impact of the barrage. Thus the water in such steam is beaten out by the barrage, and primarily by the water therein, dispersed there throughout. Thus, further separation of water from steam occurs. In the third place, the foam and foam producing substances in the jets or streams of steam and water mixture delivered by the tubes, are carried, along with the steam and water of the mixture, into the space B proper. Any foam attempting to leave such space proper, receives the impact of the moving barrage and is broken up. Similarly with spray.

Since the barrage is substantially continuous across the throat, all steam leaving the space B proper must pass through the barrage in leaving such space, on its way to the opening 11. Thus, because of the double separating effect above described, the steam leaving through opening 11 is almost freed of water. By the same token, no foam is carried along with such steam. Whatever small amount of water remains in the steam entering the space above the main baffle is removed by reason of the second baffle 2, which

causes two changes in the direction of flow of the steam on its way from the opening 11 to the outlet means, as indicated by the arrow. This ordinarily suffices to separate the remaining water. In some installations, however, it may be desirable to add additional separating means such as diagrammatically indicated at 15, this being a conventional plate type of separator or drier. In all cases the main separation occurs in advance of the opening 11, as described.

In order to drain water collecting above the main baffle, I have provided a plurality of drain pipes 14, which discharge at a point below the normal water level of the drum.

By the foregoing I have found by actual experience that I am enabled to allow the concentration of solids to build up far beyond what has heretofore been practical before it is necessary to blow down. In some installations, I have found that the concentration could be safely increased to eight times over what has heretofore been customary practice, before it became necessary to blow down.

It will be seen that the arrangement is quite flexible in that it takes care of a substantial variation in the level of water in the drum. To illustrate, as the water level sinks below the point at the line indicated, the jet from the lowermost row of tubes 7 spreads out, ensuring the maintenance of the continuous screen or barrage heretofore described. The point of complete merging may shift, but the length of the throat is such as to ensure such merger.

While the baffles are shown as composed of single pieces, they may be sectionalized if required, and they may be supported in any desired manner, so long as excessive leakage is avoided. In this connection, it is to be observed that the opening 11 should be the sole communication between spaces B and C, in the sense that there should be no other communication such as would defeat the proper functioning of the device.

In the arrangement thus far described the movement of the screen or barrage is directly counter-flow to the movement of steam from the separation space and also directly counter to the flow of any foam trying to escape from said space.

In the form shown in Figure 3, the screen or barrage moves more directly across the opening or passage affording communication between the separation space B and the space above. More specifically, the main baffle 1' in this instance rises upwardly from a point below the normal water level and adjacent to the wall of the drum opposite the inlet tubes, and then inclines rearwardly and upwardly, to a point short of the second longitudinally extending baffle 2', so as to provide an opening or passage 11' which affords the communication between separation space B and the space C.

A third longitudinally extending baffle 3 extends inwardly from the wall of the drum a short distance and cooperates with baffle 2' to provide a slot 16, extending longitudinally of the drum, through which the steam and water mixture delivered by one or more of the rows of tubes 7 is delivered in the form of a continuous sheet, screen or barrage 17 which impinges on the baffle 1' at a small angle as hereinbefore described. This sheet lies between space B and the opening or passage 11', flowing across the latter.

The operation is essentially as before described. In order for steam to leave the sep-

ration space B, it must pass through the sheet or barrage 17 and receives the impact thereof. As before, water carried in such steam is beaten out. Likewise any foam tending to leave the separation space B, receives the impact of said sheet or screen or barrage and is broken up. For most installations, the relatively small amount of water remaining in the steam as it passes through opening 11' is removed by the action of the baffle 4 which causes the steam to take a continuous path to the outlet tubes 10, with change in the direction of flow. In other installations a final separator or drier 15 such as indicated in Fig. 1 may be employed. Water separating out above the baffle 1' finds its way to the water in the drum at 18. Desirably the lower portion 11" of the baffle 1' inclines rearwardly and downwardly as shown, in order to cause the water separated out in separation chamber space B to take the course indicated generally by the arrow.

This arrangement likewise ensures the effective separation of water and concentrates and prevents carry over of foam.

In the arrangement shown in Figure 4, the main baffle 12 is substantially upright and the upper end thereof terminates short of and is spaced away from the second baffle 2'', again providing an opening 11'' which constitutes the communication between the separation space B and the space C.

As before, the third longitudinally extending baffle 3' is so disposed with reference to the baffle 2'' as to discharge the mixture delivered by one or more rows of tubes 7 in the form of a downwardly directed sheet, screen or barrage 17', which likewise impinges upon the main baffle 12 at a small angle.

It will be seen that in this arrangement, like that of Figure 3, a continuous sheet, screen or barrage moves across the opening affording communication between spaces B and C, through which all steam leaving space B must pass and with which any foam attempting to leave such space must contact and thus be broken up.

Reverting to Figure 1, the portion 1b of the main baffle 1 is turned upwardly for the reason that in some installations there may be, in addition to the tubes 7 shown, other tubes at the opposite side of the drum, discharging steam and water mixture above the normal water level in the drum. By inclining the portion 1b as shown, the arrangement may be accommodated to such an installation. In this connection the number of tubes so delivering the steam and water mixture into the throat formed by the portion 1b should not be great enough to counteract the effect of the barrage in throat 1a.

This application is a continuation in part of my application Serial No. 390,879, filed April 29, 1941.

I claim:

1. In a steam and water drum having inlet tubes at least some of which deliver a mixture of steam and water into the drum above the normal water level thereof and having steam outlet means, the combination of a main baffle and second baffle spaced from the main baffle, both baffles extending longitudinally of the drum, and end baffles, all of said baffles cooperating to divide the free region of the drum into two spaces, namely, a separating space for entering steam and water mixture and a space from which steam is discharged via the said outlet means, the only communication between the separating space and the second space being by way of the opening pro-

vided by the spacing apart of the said main baffle and said second baffle, and a third longitudinally extending baffle spaced from but cooperating with said second baffle to direct some of the mixture of steam and water entering the drum in the form of a continuous sheet moving across said opening and between it and said separating space and impinging on said main baffle, whereby all steam leaving said separating space must pass through said sheet on its way into the second space and foam in attempting to leave said separating space meets with and receives the impact of said sheet.

2. In a steam and water drum having inlet tubes at least some of which deliver a mixture of steam and water into the drum above the normal water level thereof and having steam outlet means, the combination of a main baffle and second baffle spaced from the main baffle, both baffles extending longitudinally of the drum, and end baffles, all of said baffles cooperating to divide the free region of the drum into two spaces, namely, a separating space for entering steam and water mixture and a space from which steam is discharged via the said outlet means, the only communication between the separating space and the second space being by way of the opening provided by the spacing apart of the said main baffle and said second baffle, and a third longitudinally extending baffle spaced from but cooperating with said second baffle to direct some of the mixture of steam and water entering the drum in the form of a continuous sheet moving across said opening and between it and said separating space and impinging on said main baffle, whereby all steam leaving said separating space must pass through said sheet on its way into the second space and foam in attempting to leave said separating space meets with and receives the impact of said sheet, said main baffle rising from the region of the normal water level and inclining from the vertical, the inclination with reference to the line of movement of said sheet being such that the sheet impinges on said main baffle at a small angle and is deflected downwardly.

3. In a steam and water drum having inlet tubes at least some of which deliver a mixture of steam and water into the drum above the normal water level thereof and having steam outlet means, the combination of a main baffle and second baffle spaced from the main baffle, both baffles extending longitudinally of the drum, and end baffles, all of said baffles cooperating to divide the free region of the drum into two spaces, namely, a separating space for entering steam and water mixture and a space from which steam is discharged via the said outlet means, the only communication between the separating space and the second space being by way of the opening provided by the spacing apart of the said main baffle and said second baffle, and a third longitudinally extending baffle spaced from but cooperating with said second baffle to direct some of the mixture of steam and water entering the drum in the form of a continuous sheet moving across said opening and between it and said separating space and impinging on said main baffle, whereby all steam leaving said separating space must pass through said sheet on its way into the second space and foam in attempting to leave said separating space meets with and receives the impact of said sheet, said main baffle being substantially vertically disposed and the second and third longitudinally extending baffles being so disposed

that the said sheet impinges upon said main baffle at a small angle and is deflected downwardly.

4. In a steam and water drum having steam outlet means, baffle means dividing the free region of the drum into two longitudinally extending spaces, one being a separating space for entering steam and water mixture and the other a space from which steam is discharged via said outlet means, said baffle means having one longitudinally extending edge terminating short of the drum wall to provide for an opening constituting the only communication between the said two spaces, and means for delivering steam and water mixture into said separating space across said opening and immediately in advance thereof and so disposed with reference to the baffle means as to cooperate therewith to form the said so delivered steam and water mixture while on its incoming course, into a continuous, longitudinally extending barrage interposed in advance of said opening and screening it from the steam separating space and extending across the path of all steam leaving the separating space on its way into the second space to the outlet means, whereby all steam leaving the separating space must first pass through said barrage, and foam attempting to leave said separating space meets with and receives the impact of said barrage.

5. In a steam and water drum having steam outlet means, baffle means dividing the free region of the drum into two longitudinally extending spaces, one a separating space for incoming steam and water mixture and the other a space from which steam is discharged via said outlet means, said baffle means having one longitudinal edge portion terminating short of the drum wall to provide for an opening constituting the only communication between said two spaces, said edge portion cooperating with the water in the drum

to constitute a throat for the steam separating space, and inlet tubes delivering steam and water mixture into said throat, the said tubes being disposed with reference to each other, to the water in the drum and to said longitudinal edge portion of the baffle so that steam and water mixture on its incoming course is formed into a continuous longitudinally extending barrage in the throat in advance of and adjacent to said opening and screening it from the steam separating space, said barrage moving counter to steam leaving said steam separating space on its way to said opening and toward the outlet means, whereby all steam leaving said separating space on its way to the outlet means must first pass through said barrage and foam attempting to leave said separating space meets with and receives the impact of said barrage.

6. The method of separating steam and water in a steam and water drum having a steam separating space for entering steam and water mixture and an outlet passage for steam, which comprises continuously delivering steam and water mixture into the separating space of the drum and continuously forming it on its inward course into a continuous barrage immediately in advance of said passage, which barrage extends longitudinally of the drum, screens the said passage from the steam separating space of the drum, and moves in a direction with respect to said passage such that steam and water of the barrage cannot pass directly to said passage, whereby all steam leaving the separating space via said outlet passage must first pass through said barrage and all foam in attempting to leave said separating space meets with and receives the impact of said barrage.

PALMER B. PLACE.
